UNITED STATES PATENT OFFICE.

JOHN C. ANDERSON, OF EUREKA, CALIFORNIA.

GASOLENE-DISPENSER.

1,325,603.

Specification of Letters Patent. Patented Dec. 23, 1919.

Application filed May 1, 1919. Serial No. 283,939.

To all whom it may concern:

Be it known that I, JOHN C. ANDERSON, a citizen of the United States of America, residing at Eureka, in the county of Humboldt and State of California, have invented certain new and useful Improvements in Gasolene-Dispensers, of which the following is a specification.

This invention relates to feed pipes for gasoline tanks and more particularly to that class of pipes used for what is commonly known as the vacuum feed and has for its object the reservation within the tank of all the gasoline below a predetermined level as a reserve supply and the giving of an alarm when such level of the gasoline in the tank is reached, which reserve supply may be drawn upon for use at will. For the purpose of illustration, I will show in the accompanying drawings and describe herein my invention as applied to a gasoline tank for feeding gas to an internal combustion engine, but it will be evident that the device may readily be used for other purposes.

In the drawings:

Figure 1 shows my device as applied to a gasoline tank with portions of the tank broken away.

Fig. 2 is a top plan view of the device with a portion of the service pipe.

Fig. 3 is a bottom plan view of the inner tubular portion of my device taken on line 3-3 Fig. 1.

Reference numeral 1 of the drawings represents an ordinary gasoline tank. 2 and 3 are sections of the feed pipe coupled together with their ends in spaced relation to each other by a tubular coupling 4 which is screw threaded on its inner surface for a portion of its length and intermediate the ends thereof as at 5 thus forming a continuous outlet from a point above the plane of the bottom of the tank through the top thereof where it connects with the service pipe 10. 6 is a short rotatable tubular member screw threaded on its outer face and interposed between the ends of sections 2 and 3 and is adapted to engage the screw threaded portion of the inner face of coupling member 4 in which it is adapted to be rotated by means of the operating rod 7 which carries at its upper end grip 8.

9 is a bushing in the top of the tank to receive therethrough section 2.

10 is a service pipe leading to an internal combustion engine (not shown),

11 is a port in member 6 which may be brought into registering or non-registering position with port 12 of coupling 4 by rotating grip 8.

The device as described herein being applied to a vacuum feed, it will readily be seen that if grip 8 of the operating rod 7 is turned into such a position as to result in port 11 of member 6 being brought into alignment and registry with port 12 of coupling 7 and the tank being filled with gasoline to a point above said ports that the gasoline will be drawn into section 2 of the feed pipe by reason of a vacuum created within service pipe 10 beyond the gasoline tank and that when sufficient gasoline has been withdrawn from the tank to lower its level to or below the said ports that air will be admitted to section 2 of the feed pipe thereby breaking the vacuum and consequently destroying its action and stopping the flow of gasoline therethrough to the carburetor thereby causing the engine to stop when grip 8 may be turned into such position as to throw port 11 out of alignment or registering position with port 12 when the vacuum action will be exerted upon the reserve supply of gasoline within the tank through the bottom portion of section 3 of the feed pipe.

I claim:

1. A tank having a tubular member extending downwardly therein, a second tubular member in alignment therewith and spaced from the lower end thereof, and a valve interposed between the said tubular members.

2. A tank having a tubular member extending downwardly therein, a second tubular member in alignment therewith, a spacing member interposed between the said tubular members and a valve carried by the said spacing member.

3. A tank having a tubular member extending downwardly therein, a second tubular member in alignment therewith, a spacing member interposed between the said tubular members, a valve carried by said spacing member and means for operating said valve.

4. A tank having a tubular member extending downwardly therein, a second tubular member in alignment therewith, a spacing member interposed between the said tubular members, having a port through the walls thereof, and a tubular member con-

centrically within said spacing member having a port through the wall thereof, said ports being adapted to be brought into registration with each other.

5. A tank having a tubular member extending downwardly therein, a second tubular member in alignment therewith and spaced from the lower end thereof, an internally threaded spacing member having a

port in its wall interposed between said tubular members, a tubular member concentrically within said spacing member and having a port in its wall, and means for bringing said ports into registration with each other.

In testimony whereof I affix my signature.

JOHN C. ANDERSON.
